UNITED STATES PATENT OFFICE.

KEENE LUTES, OF DANVILLE, KENTUCKY.

DESIGN FOR A ROAD-SIGN.

52,332.

Specification for Design.

Patented Aug. 27, 1918.

Application filed May 10, 1918. Serial No. 233,814. Term of patent 7 years.

To all whom it may concern:

Be it known that I, KEENE LUTES, a citizen of the United States, residing at Danville, in the county of Boyle and State of Kentucky, have invented a new, original, and ornamental Design for a Road-Sign, of which the following is a specification, reference being had to the accompanying drawing, forming part thereof.

The figure is a perspective of a road sign, showing my new design.

I claim:

The ornamental design for a road sign, as shown.

KEENE LUTES,

Copies of this patent may be obtained for five cents each, by addressing the "Commissioner of Patents, Washington, D. C."
